UNITED STATES PATENT OFFICE.

HERBERT W. DAUDT, OF PENNS GROVE, ALFRED E. PARMELEE, OF CARNEYS POINT, AND WILLIAM S. CALCOTT, OF PENNS GROVE, NEW JERSEY, ASSIGNEES TO E. I. DU PONT DE NEMOURS & COMPANY, OF WILMINGTON, DELAWARE, A CORPORATION OF DELAWARE.

MANUFACTURE OF TETRA-ETHYL LEAD.

No Drawing.

Application filed November 2, 1925. Serial No. 66,392.

This invention pertains to an improvement in the manufacture of tetra-ethyl lead by the interaction of lead-sodium alloy with ethyl chloride. Specifically it relates to the addition of certain dispersing substances to the mass or sludge resulting from the said reaction, whereby a change in physical condition of the mass is effected which greatly facilitates its handling and the separation 10 of the tetra-ethyl lead therefrom by distillation.

Heretofore, the nature of the mass has made handling and satisfactory separation very difficult. For instance, in the preparation 15 of tetra-ethyl lead by the interaction of mono-lead-sodium alloy and ethyl chloride, the lead sodium alloy is commonly placed in an autoclave with liquid ethyl chloride where the temperature is maintained, generally, between 30 and 60° C. until completion 20 of the reaction. The resulting mass consists of a lead-containing sludge in which the particles of lead tend to cohere and, by forming balls and sheets, render effective agitation impractical or impossible.

We have found that, upon the addition 25 of our dispersing agents subsequently to the completion of the described reaction, the physical condition of the solid material is so changed that it is adapted for ready agitation, and may be handled with relative ease. By reason of the improved condition 30 of the mass, the tetra-ethyl lead may be efficiently separated by steam distillation while the mass is undergoing agitation. The changed condition appears to be due to the formation of a film or coating on the surface 35 of the solid material, which film functions to prevent agglomeration of the metallic lead. It is to be understood, however, that this theory is advanced merely as a probable 40 explanation of the action of the dispersing agents, and that our invention is independent of the correctness thereof.

The desired change in physical condition 45 may be brought about by either an agent exerting a purely physical effect, such as would result from the presence of a protective colloid, or from the absorption of an oil or solvent by the solid mass, or it 50 may be brought about by a substance which

reacts chemically with the lead, or the lead compounds present upon its addition.

Such dispersing substances as are suitable for our purpose, may therefore, be conveniently classified in two groups: (1) those substances whose use is advantageous because of their physical effect, as glue, agar-agar, or other gums, Turkey red oil and various inert oils, such as engine oil, lard oil or benzene, or reasonably high boiling solvents such as toluene, and (2) substances which produce the desired effect because of a chemical reaction as inorganic salts generally having the formula MR, where M is any metal forming soluble salts and R any acid radical which forms insoluble lead salts. Examples of salts having the formula MR and suitable for use in the process are sodium sulfide, sodium carbonate and sodium sulfate, or the corresponding potassium salts.

In order to set forth our invention in detail, the following typical examples of actual embodiments thereof are furnished. It is to be understood, of course, that such examples are purely illustrative.

Example A (action apparently purely physical).

1 part of lead mono sodium alloy is placed in an autoclave and the temperature raised to 40° C. To this is slowly added in the space of two hours 125% of the theoretical amount of ethyl chloride required for the conversion of the lead sodium alloy to tetra-ethyl lead. After all the ethyl chloride has been added, the charge is warmed for three hours to 60° and then cooled to 25° C. After the charge is thoroughly cool any pressure is released and the charge is drowned in water to which has been added engine oil equal in weight to 3-10% of the total weight of lead in the charge. The tetra-ethyl lead is removed by steam distillation from the agitated mass.

Example B (a chemical change involved).

In the manufacture of tetra-alkyl lead by the interaction of lead sodium alloy with ethyl chloride, lead sodium alloy and ethyl chloride are allowed to react as stated in

Example A. The reaction mass is then drowned in water to which has been added sodium sulfite crystals equal in weight to five percent of the total lead present in the charge. The tetra-ethyl lead is separated by steam distillation from the agitated mass.

Example C.

10 The two types of dispersing compounds classified above respectively as reacting chemically and physically, may be used together, as in the example following:

15 In the manufacture of tetra-alkyl lead by the interaction of lead sodium alloy and ethyl chloride, lead sodium alloy and ethyl chloride are allowed to react as stated in Example A. The reaction mass is then drowned in water to which has been added sodium sulfite equal to three to ten percent 20 of the weight of lead and engine oil to the extent of five percent of the weight of lead. The lead tetra-ethyl is recovered by steam distillation of the agitated mass.

25 When the dispersing agents are employed as directed and exemplified, the cohesion of the lead particles with attendant formation of large balls and sheets is largely prevented, with the result that the mass is much more finely divided. By reason of this fact 30 the tendency of appreciable quantities of the lead tetra-ethyl to remain occluded in the mass is largely overcome. The finely divided mass also, as has been pointed out, may be readily agitated during the distillation, and the thoroughness of the separation 35 very materially augmented.

We claim:

1. In the manufacture of tetra-ethyl lead by the interaction of ethyl chloride and 40 mono-sodium-lead, the improvement which comprises adding to the reaction mass, subsequently to the completion of the reaction, a dispersing substance adapted to form a water insoluble film on the surface of the 45 particles of said mass.

2. In the manufacture of tetra-ethyl lead by the interaction of ethyl chloride and mono-sodium-lead, the improvement which 50 comprises adding to the reaction mass, subsequently to the completion of the reaction, a substance adapted to substantially preclude cohesion of the lead particles present therein.

3. In the manufacture of tetra-ethyl lead by the interaction of ethyl chloride and mono-sodium-lead, the improvement which 55 comprises adding to the reaction mass, subsequently to the completion of the reaction, a dispersing substance adapted to render 60 said mass susceptible of agitation during steam distillation.

4. The process of manufacturing tetra-ethyl lead which comprises effecting a reaction between mono-sodium-lead and ethyl 65 chloride and drowning the resulting mass

in a liquid containing a substance adapted to preclude cohesion of the lead particles present in the mass.

5. The process of manufacturing tetra-ethyl lead which comprises effecting a reaction between mono-sodium-lead and ethyl chloride, drowning the resulting mass in a liquid containing a substance adapted to preclude cohesion of the lead particles present in the mass, and distilling off the tetra-ethyl 75 lead while agitating.

6. In the manufacture of tetra-ethyl lead by the interaction of ethyl chloride and mono-sodium-lead, the improvement which comprises adding to the reaction mass, subsequently to the completion of the reaction, an inert substance adapted to substantially preclude cohesion of the lead particles present 80 therein by physical effect.

7. The process of manufacturing tetra-ethyl lead which comprises effecting a reaction between mono-sodium-lead and ethyl chloride and drowning the resulting mass in a liquid containing an inert oil in sufficient quantity to preclude cohesion of the 90 lead particles present in the mass.

8. The process of manufacturing tetra-ethyl lead which comprises effecting a reaction between mono-sodium-lead and ethyl chloride and drowning the resulting mass 95 in a liquid containing engine oil in an amount equal in weight to from 3 to 10% of the total weight of lead present.

9. The process of manufacturing tetra-ethyl lead which comprises effecting a reaction between mono-sodium-lead and ethyl chloride and drowning the resulting mass in a liquid comprising a mixture of substances adapted to function to preclude cohesion of the lead particles present in the mass, one 100 of said substances functioning by physical effect, and another functioning by chemical action.

10. The process of manufacturing tetra-ethyl lead which comprises effecting a reaction between mono-sodium-lead and ethyl chloride and drowning the resulting mass in a liquid comprising engine oil and sodium sulfite.

11. The process of manufacturing tetra-ethyl lead which comprises effecting a reaction between mono-sodium-lead and ethyl chloride and drowning the resulting mass in a liquid comprising engine oil and sodium sulfite, both said oil and said sulfite being present in amounts ranging over 3% of the 115 total weight of lead in the mass.

12. A sludge comprising the products resulting from the interaction of mono-sodium-lead and ethyl chloride, together with 120 a dispersing agent.

13. A sludge comprising the products resulting from the interaction of mono-sodium-lead and ethyl chloride, together with 125 an inert dispersing agent.

14. A sludge comprising the products resulting from the interaction of mono-sodium-lead and ethyl chloride, together with engine oil.

an inert dispersing agent and a chemically active dispersing agent.

In testimony whereof we affix our signatures.

HERBERT W. DAUDT.
ALFRED E. PARMELEE.
WILLIAM S. CALCOTT.

15. A sludge comprising the products resulting from the interaction of mono-sodium-lead and ethyl chloride, together with
